UNITED STATES PATENT OFFICE

F. HUGH WARD, OF ROCKFORD, ILLINOIS

GAME

Application filed December 6, 1929. Serial No. 412,054.

This invention relates to a racing game. The principal object of my invention is to provide a game simulating an actual horse race as closely as possible. With this object in view I have provided a miniature race track marked off in a certain number of lanes in each of which a game piece or symbol corresponding to a horse is played and arranged to be advanced on each play according to the throwing of dice. I realize that racing games of this general description have been proposed before, but most of them involved such features that there was no close similarity to an actual horse race, and, consequently, they were not particularly popular. In the game of my invention, the lanes for the different horses are marked off into different numbers of spaces, the inside lane along the rail having the least number of spaces, and the outside lane having the greatest number, and those in between having spaces proportionately greater in number than the inside lane according to how far removed they are from said lane. The different lanes are given distinctive colors, and dice of the same distinctive colors are provided, one for each lane and all numbered alike. Thus, when the dice are thrown, the different horses are advanced according to the numbers appearing on the different dice. The horse on the inside lane, the "favorite", has the least number of jumps to make to reach the finish line, and the others in the other lanes have greater numbers of jumps to make according to their lanes. Thus, there is injected into this game much of the element of chance that makes horse races so popular. For example, every horse has a chance to either "win", "place", or "show", and the odds are, of course, more in favor of the favorite and less in favor of the horse in the outside lane. According to my invention, players may select horses to "win", "place", and "show", and in accordance with a predetermined schedule of odds for the different horses.

The invention is illustrated in the accompanying drawing, in which—

Figure 1 is a plan view of a game board or card embodying my invention, and

Fig. 2 is a perspective view of the dice arranged to be used in connection therewith.

The game board or card 3, which may, for example, be lithographed for the sake of cheapness, has thereon a representation of a race track at 4, and below it or to one side, 55 a schedule of odds 5. 6 is the start-finish line at one end of the home stretch 7, the track being preferably made oblong like an actual race track, having a back stretch 8 and turns 9 and 10. According to my invention, the track 4 is marked off into any suitable number of separate lanes preferably differently colored, as for example, the inside lane 11 is shown green; the next lane 12, yellow; the next 13, blue; the next 14, brown; the next 15, 65 white; and the outside lane 16, red. Now, these different lanes, each distinctively colored as stated, are marked off into a certain number of spaces, starting with say, 30, for the inside lane 11 along the rail, and increasing the number of spaces for the other lanes in proportion as they are more remote from the inside lane, so that lane 12 has say, 32 spaces; lane 13, 34 spaces; lane 14, 36 spaces; lane 15, 38 spaces, and lane 16, 40 spaces, 70 measuring from the start-finish line around the track and back to said line. Game pieces or symbols corresponding to horses are provided for the different lanes, and these may or may not be colored, but preferably are, 75 to match the lanes. The game pieces are numbered 11' to 16'. Associated with these game pieces, I provide dice, or any other suitable play-controlling devices, colored to match the lanes, numbered 21 to 26, respectively. The dice are all numbered alike—0 to 5. Now, to complete the game, I have marked off the schedule 5 in six columns colored to correspond with the lanes and the dice, as shown, and numbered 31 to 36, re-

spectively. The different figures in each column are for "win", "place", and "show", as indicated, and it will be noticed that the odds are increased in proportion to the number of spaces in the particular lane with which the 5 column in the schedule is associated, and, of course, the odds are less to "place" than to "win", and still less to "show".

In playing the game, any number of players, that is, two or more, can play. One of the 10 players may be elected banker and given a certain number of chips or tokens to allot a certain number to each player. Each of the players selects a certain horse to "win", another to "place", and another to "show", and, accordingly, deposits two chips in each of three places on the schedule 5. Then, the 15 horses 11' to 16' are placed on the line 6 for the start of the race. The banker throws the 20 dice, and the horses are advanced after each throw according to the numbers appearing on the dice. The horses appear in Fig. 1 advanced according to the throw of the dice shown in Fig. 2. Thus, horse 11' has been 25 advanced one jump to agree with dice 21; horse 12' three jumps to agree with dice 22; horse 13 two jumps to agree with dice 23, etc., the horse 16' being shown advanced five jumps to agree with dice 26. It will be observed that one horse of the six has not been 30 advanced, owing to the fact that 0 has been thrown with the dice 24. It will be evident from observation of the horses as they appear in relation to one another after the first 35 throw of the dice how the game offers much of the excitement of an actual horse race, and, furthermore, how the chances of the different horses to "win", "place" or "show" may look favorable or unfavorable during the progress 40 of the game. At the finish of the race the banker gives the player whose horse has won, a number of chips corresponding to the number given on the schedule. Thus, if the blue horse 13' wins, ten chips are given in return 45 for the two placed in that space at the beginning of the race, and in like manner the banker gives chips to those whose horses were in to "place" or to "show". All of the other 50 chips go to the banker. Obviously, several players can select a certain horse to "win", to "place", or to "show". In case two or more horses tie at the finish of a race, the one with the lowest odds is regarded as first; the one with the next lowest, second; and so on. If 55 one horse wins but there are two tied to "place", whichever one of the two that are tied has the lower odds is considered second, and the other third. In like manner there may be two tied to "show". In that event, 60 whichever one has the lower odds is considered third in the race. The rules may be varied from what has just been given to suit the preference of the players. Furthermore, the odds given in the schedule 5 are not necessarily fixed, but may be changed as desired.

The following claims are drawn with a view to covering the invention in such terms as to embrace all legitimate modifications and adaptations such as are apt to occur to others after my disclosure.

70

I claim:

1. In a horse racing game or the like, the combination of a game board embodying a track having a start and finish line and divided into a series of lanes, each in turn divided into successive spaces, there being different predetermined numbers of spaces in the said lanes, a schedule of odds divided lengthwise into a series of sections equal in number to the lanes, there being one section 80 associated with each lane the schedule being divided cross-wise so as to provide three spaces in each section, one suitably designated for win, the next for place, and the next for show, the spaces having suitable legends therein 85 pertaining to odds, the odds being proportioned in two ways, namely, in proportion to the number of spaces in the lanes and as between win, play and show, game pieces to represent horses, one for each lane, and play 90 controlling devices, such as dice, one for each game piece and all numbered alike and arranged to be played at one time so as to determine the simultaneous advancement of the pieces in the lanes as chance determines, each 95 lane and the schedule section and die related thereto being colored alike in contrast to the others, the differently colored sections of the schedule being arranged in the same order as the differently colored lanes.

100

2. In a racing game, the combination of a game board embodying a track having a start and finish line and divided into a series of lanes, each in turn divided into successive spaces, there being different predetermined 105 numbers of spaces in said lanes, a schedule of odds divided lengthwise into sections equal in number to the lanes, there being one section associated with each lane and the sections having suitable legends therein pertaining to 110 odds, game pieces, one for each lane, and play controlling devices, such as dice, one for each game piece and all numbered alike and arranged to be played at one time so as to 115 determine the simultaneous advancement of the pieces in the lanes as chance determines, each lane and the schedule section and die related thereto being colored alike in contrast to the others, and the differently colored sections of the schedule being arranged in the same order as the 120 differently colored lanes.

115

3. In a racing game, the combination of a game board embodying a track having start and finish points and divided into a series of lanes, each in turn divided into successive 125 spaces, a schedule of odds divided lengthwise into sections equal in number to the lanes, there being one section associated with each lane and the lanes having suitable legends therein pertaining to odds, game pieces, one 130

130

for each lane, and play controlling devices, such as dice, one for each game piece, arranged to be played together to determine the advancement of the pieces in the lanes as chance determines, each lane and the schedule section and die related thereto being colored alike in contrast to the others, and the differently colored sections of the schedule being arranged in the same order as the differently colored lanes.

10 In witness of the foregoing I affix my signature.

F. HUGH WARD.
